DRY-KILN.

1,095,187.

Specification of Letters Patent.

Patented May 5, 1914.

Application filed December 21, 1912. Serial No. 738,090.

To all whom it may concern:

Be it known that I, JOHN S. BURCH, a citizen of the United States, and a resident of the city of Chicago, county of Cook, and State of Illinois, have invented certain new and useful Improvements in Dry-Kilns, of which I do declare the following to be a full, clear, and exact description, reference being had to the accompanying drawings, forming part of this specification.

The present invention, while susceptible of wider application, has relation more especially to that class of dry kilns intended for drying articles such as piano cases, carriage bodies, or the like, that have been painted and varnished and which require to be carefully and uniformly dried.

The invention consists in the features of improvement hereinafter described, illustrated in the accompanying drawings and particularly pointed out in the claims at the end of this specification.

Figure 1 is a view in vertical cross section through a drying kiln embodying my invention. Fig. 2 is an enlarged detail view through the lower portion of the kiln at one side. Fig. 3 is a view in horizontal section on line 3—3 of Fig. 1 (showing a part only of the kiln), portions being broken away to illustrate subjacent parts. Fig. 4 is a view through the upper portion of the kiln on line 4—4 of Fig. 1. Fig. 5 is an enlarged detail view in section through some of the air inlet ports adjacent the bottom of the kiln.

The main structure of my improved kiln comprises a drying chamber 10, the outer walls of which may be formed of two thicknesses with an air space between them. Above the bottom 11 of the kiln are arranged the usual heating pipes 12 that may be conveniently supported upon rods 13 extending transversely of the kiln and resting upon suitable stringers 14. Upon the bottom 11 of the kiln, at each side thereof, extend the stringers 15 through which are preferably formed the air induction ports to be presently described. Above the heating coils 12 extend metal plates 16 provided at intervals with perforations 17. Above the perforated plates or floor 16 extends a reticulated or foraminous sheet 18 consisting preferably of a wire mesh that may be sup-

ported upon rods 19 that are shown as resting on blocks 20 arranged at convenient intervals. Above the wire sheet 18 is arranged the upper member of the floor that is composed of perforated plates 22. These plates are shown as supported at the sides of the kiln upon angle bars 23 and at intervals between these angle bars by T-bars or supports 24 that are shown as resting upon the supporting rods or pipes 13. The edges of the plates 22 abut each other and are riveted to the upper flanges of the T-bars 24, so that the plates provide a floor with a smooth surface over which trucks containing the articles to be dried may be moved without any severe jarring of such articles.

By reference to Fig. 3 of the drawings it will be seen that the upper and lower floor plates 16 and 22 have their perforations arranged out of vertical line, the purpose of this being to break up the air currents and effect a uniform distribution of the heated air as it rises through the floor of the kiln and for this reason also it is preferred to employ the wire fabric between the upper and lower perforated plates. As shown, the upper plates 22 are preferably provided with smaller and more numerous perforations than the plates 16, as by this arrangement the air is more uniformly distributed and the disadvantage of having large perforations in the upper plate is avoided.

Through the stringers 15 at the sides of the kiln are formed a number of inlet ports 30 (see Fig. 5) extending, preferably, from end to end of the kiln at each side thereof, and at suitable distances apart. These inlet ports 30 open, as shown, beneath the floor of the kiln and the flow of air through these inlet ports is regulated by a sliding perforated valve or plate 32 that is guided by the upper and lower overlapping guide plates 33 and 34, (see Fig. 2). To this sliding plate or valve 32 is attached an operating rod 36 that extends through a slot formed in the stringer 15 to a point outside the wall of the kiln, so that the attendant by shifting the rod 36 laterally can move the valve 32 so as to regulate the flow of air through the inlet ports 30. The top of the kiln is also preferably formed of double thicknesses, as shown, suitable stringers 40

being placed between the thicknesses of the top. Through the top of the kiln are formed outlet ports 42 that preferably extend through the stringers 40. These outlet ports 42 are preferably controlled by a sliding, perforated valve or plate 43 similar to the valve 32 before described. Each of these valves 43 (one or more may be employed), is shown as supported and guided by overlapping guide plates 44 and 45 arranged upon the under face of the inner thickness of the top of the kiln. Each valve 43 has connected thereto a rod 46 that extends through the top of the kiln and, preferably, 10 each of the rods 46 is bent, as shown in Fig. 4, and extended to one side of the kiln, the outer end of the rod 46 being pivotally connected to a hand lever 47 that is pivoted to a bracket 48 attached to the side of the 15 kiln. By means of the hand lever 47 and rod 46, the valve 43 can be conveniently shifted so as to regulate the extent of opening of the outlet ports 42. By arranging the valves 32 and 43 within the kiln, the 20 danger of these valves being tampered with is avoided.

From the foregoing description it will be seen that by means of the valves 32 and 43 the volume and flow of air through the body 25 of the kiln can be accurately regulated. It will be seen also that as the air enters beneath the floor of the kiln, it will be heated and will be delivered into the body of the kiln uniformly and in very fine streams, so 30 that no part of the kiln will be subjected to excessive drafts and a uniform distribution of the heat throughout the body of the kiln will thus be insured.

Preferably, there is placed in the top of 35 the kiln a series of pipes or coils 50 for the passage of cold water or other chilling fluid. These pipes are supported upon suitable brackets 51 and beneath these pipes there is suspended by brackets 52 a drip pan 53 40 adapted to receive the water of condensation. From the bottom of the drip pan 53 leads a discharge pipe 54 that will be extended outside the wall of the kiln. It will be understood, of course, that the pipes 50 will be 45 provided with a cock (not shown) whereby the cold liquid through the pipes may be admitted or regulated as desired. Preferably, the inner wall of the kiln is faced with a sheet metal lining, although this is not essential to my invention.

It will be understood that the precise details of construction above set out may be varied without departing from the spirit of the invention, and that features of the invention may be employed without its adoption as an entirety.

Having thus described my invention, what

I claim as new, and desire to secure by Letters Patent, is:—

1. A dry kiln comprising a drying chamber having air inlets and outlets at its bottom and top, heating pipes adjacent the bottom of said chamber and a floor above said heating pipes comprising upper and lower perforated plates, the perforations of said plates being arranged out of alignment. 65

2. A dry kiln comprising a drying chamber having air inlets and outlets at its bottom and top, heating pipes adjacent the bottom of said chamber and a floor above said heating pipes comprising perforated metal plates laid together with their edges abutting and supports extending below said plates to which the abutting edges of said plates are secured. 75

3. A dry kiln comprising a drying chamber having air inlets and outlets at its bottom and top, heating pipes adjacent the bottom of said chamber and a floor above said heating pipes comprising upper and lower perforated plates, and a reticulated fabric interposed between said upper and lower plates. 85

4. A dry kiln comprising a drying chamber, a series of heating pipes at the bottom of said chamber, a perforated floor above said pipes, a series of inlet ports in the sides of said chamber below said floor, a series of outlet ports at the upper portion of said chamber, perforated slide valves at the inner ends of said inlet and outlet ports, guides for said valves fixed to the inner surfaces of the walls of said chamber and shifter rods connected to said valves and extending outside of said chamber, substantially as 95 described. 100

5. A dry kiln comprising a drying chamber having air inlets at its lower portion and air outlets at its upper portion, means for controlling the flow of air through said inlets and said outlets, means for heating the air admitted to the chamber through said inlets, and means for uniformly distributing the heated air throughout said chamber comprising a floor formed of upper and lower perforated plates, the perforations of said plates being arranged out of alignment. 105 110

6. A dry kiln comprising a drying chamber having air inlets and outlets at its bottom and top, heating pipes within said chamber, a slide valve arranged within said chamber for controlling the air outlets at its top, a rod extending from said slide valve to a point outside said chamber and a pivoted hand lever connected to said rod. 115
